(57) **CLAIM**

The ornamental design for a sprayer, as shown and described.

DESCRIPTION

FIG. 1 is a front and top perspective view of a sprayer that has the design.

FIG. 2 is an elevation view of one side of the sprayer, the opposite side view being a minor image except for parts of the sprayer seen in broken lines.

FIG. 3 is a top plan view of the sprayer.

FIG. 4 is an elevation view of one end of the sprayer; and, FIG. 5 is an elevation view of the other end of the sprayer. The broken line showing of parts of the sprayer is to illustrate unclaimed parts of the sprayer, and forms no part of the claimed design.
